UNITED STATES PATENT OFFICE.

BURT A. CHUBBUCK, OF MEDINA, NEW YORK.

DESIGN FOR A CLOCK-CASE.

No. 38,514.

Specification for Design.

Patented April 9, 1907.

Application filed February 23, 1907. Serial No. 359,035. Term of patent 7 years.

To all whom it may concern:

Be it known that I, BURT A. CHUBBUCK, of Medina, in the county of Orleans and in the State of New York, have invented a certain new and ornamental Design for a Clock-Case; and I do hereby declare that the following is a full, clear, and exact description thereof, reference being had to the accompanying drawings, in which—

Figure 1 is a perspective view of a clock-case embodying my design, and Fig. 2 a front view of the same.

What I claim is—

The ornamental design for a clock-case.
BURT A. CHUBBUCK.
